CLAIM

The ornamental design for a mounting platform for a win 94 rifle, as shown and described.

DESCRIPTION

FIG. 1 is a perspective view of a mounting platform for a win 94 rifle showing my new design;
FIG. 2 is a perspective front elevational view thereof;
FIG. 3 is a perspective right side elevational view thereof;
FIG. 4 is a perspective left side elevational view thereof; and,
FIG. 5 is a perspective top plan view thereof.
